GUSTAF W. OLSON AND CHARLES F. KROON, OF MINNEAPOLIS, MINNESOTA.

HUMIDIFIER ATTACHMENT FOR RADIATORS.

1,293,523.

Specification of Letters Patent.

Patented Feb. 4, 1919.

Application filed January 19, 1918. Serial No. 212,559.

To all whom it may concern:

Be it known that we, GUSTAF W. OLSON and CHARLES F. KROON, citizens of the United States, residing at Minneapolis, in the county of Hennepin and State of Minnesota, have invented certain new and useful Improvements in Humidifier Attachments for Radiators; and we do hereby declare the following to be a full, clear, and exact description of the invention, such as will enable others skilled in the art to which it appertains to make and use the same.

Our invention has for its object to provide a simple and efficient humidifier for attachment to radiators; and to such ends, the invention consists of the novel construction and combination of parts hereinafter described and defined in the claim.

It is a well known fact that the air in modern homes and in all buildings heated by steam plants and radiators or by hot water systems, for that matter, is very dry and contains very much less moisture than is required for the comfort and best health of human beings. In fact, tests have shown that the air in cold weather in heated dwellings and buildings is usually found as dry as that in the Sahara Desert. Various devices have been provided for supplying moisture, but so far as we are aware, they have either been entirely impracticable or have failed to supply anywhere near the required moisture to be effective or to restore to the air the amount of moisture that it should have.

Our so-called humidifier is adapted for ready application to ordinary radiators and it is so connected to the steam or water pipes that supply the radiator that the temperature of the water in the humidifying receptacle may be regulated to the extent necessary to positively produce the required evaporation of water into the air.

The invention in its preferred form is illustrated in the accompanying drawings wherein like characters indicate like parts throughout the several views.

Referring to the drawings,

Figure 1 is a view in side elevation showing a radiator with one of our improved humidifiers applied thereto, some parts being broken away;

Fig. 2 is a plan view of the parts shown in Fig. 1; and

Fig. 3 is an end elevation of the said parts with some portions broken away and some shown in section.

The radiator is indicated, as an entirety, by the numeral 4. The steam pipe which leads to the radiator is indicated by the numeral 5 and the steam pipe that leads from the radiator is indicated by the numeral 6. The customary valve 7 is connected to the pipe 5 adjacent to the radiator.

Our attachment comprises a large open-topped water containing pan 8, preferably of sheet metal. This pan is arranged to rest directly on the upper portion of the radiator sections, and to hold the same in position, and for other reasons, we provide a sheet metal hood 9 which has a large opening 65 through which the water pan 8 is inserted. This hood 9 is spaced from the top of the radiator sections and at its front edge projects preferably a little below the top of the radiator sections. At its back, it is formed 70 with a depending deflecting plate 10 that extends against the wall 11 and prevents the upward circulation of currents of air at the top of the radiator, thereby preventing dust from being carried onto the wall by the upwardly moving currents of hot air. At its ends, the hood 9 is provided with side plates that join with the deflecting plate 10 and cover portions of the upper outer face of the end sections of the radiator. The hood 9 75 serves to retard enough of the hot air to greatly assist in heating the water in the water pan.

A branch steam pipe 12 leads from the live steam supply pipe 5 at a point outward 80 of the valve 7, thence upward and through the water pan and thence downward and is connected to the return pipe 6. That portion of the branch steam pipe 12 that is immersed in the water of the pan 8 insures 85 heating of the water to the proper temperature to produce evaporation, and preferably is formed with a manifold bent to increase its radiating surface within the pan. On its receiving side, the branch pipe 12 is provided with a valve 13, by means of which it may be entirely closed or opened to any desired extent for the regulation of the amount of steam delivered to said pipe. Preferably, the water pan 8 is provided with 90 an open cover plate 14 such as a heavy woven wire screen. This screen or open plate prevents articles from falling into the water and permits certain articles to be set on top of the pan, if desired.

Obviously, with the above arrangement of the pipes, valves and water pan, it is pos-

2

sible to cause steam to be delivered through the pipe 12, and hence, the water in the pan to be heated even when the main steam supply valve 7 to the radiator is closed. 6 This is important, because, as has been found in practice in very immoderate weather, not only can the proper moisture be supplied to the air, but the so-called humidifier may be used as a small heater. 10 When, for example, the valve 7 is closed and the valve 13 is open, a small amount of steam will be kept constantly flowing through pipe 12, and by heating the water in the pan and by the heat radiating from 15 the exposed portion of the pipe 12, a very perceptible amount of heat will be radiated into the room. Even when the valve 7 is open, and the radiator operating to its maximum efficiency, the humidifier operates as an 20 auxiliary heater which increases the total heating capacity of the other radiator. From this last statement, it will follow that having less sections, or sections of less 25 radiating capacity may be employed for use in connection with the humidifier than when used without the humidifier. Of course, the above described arrangement of valves also makes it possible, if found desirable at any 30 time, to cut off the supply of steam to the humidifier through the branch pipe 12.

In the description of the drawings the radiators are assumed to be heated by steam, but it should be understood that hot water might be the heating medium. It will be 35 noted that when the parts are coupled up, as described and shown in the drawings, the pipe 12 holds the pan 8 in position and the pan 8 holds the hood in position on top of the 40 radiator.

What we claim is:

The combination with a radiator having supply and return pipes connected thereto, of a hood seated on and fitted over the upper portion of said radiator, a water containing 45 evaporating pan extended through the upper portion of said hood and seated on said radiator, and a branch pipe connected to said supply and return pipes and extended through said hood and said pan and the wa- 50 ter therein contained, said branch pipe serving to transmit heat to the water in said pan and serving to hold said pan interlocked to said hood and hence, the said hood positioned on said radiator.

In testimony whereof we affix our signatures in presence of two witnesses.

GUSTAF W. OLSON.
CHARLES F. KROON.
